NILS EMEL NORSTROM, OF CHICAGO, ILLINOIS, ASSIGNOR TO CASPER L. REDFIELD,
TRUSTEE, OF CHICAGO, ILLINOIS.

PROCESS FOR VAPORIZING LIQUIDS.

1,323,308.

Specification of Letters Patent.

Patented Dec. 2, 1919.

Application filed January 15, 1916. Serial No. 72,195.

To all whom it may concern:

Be it known that I, NILS EMEL NORSTROM, a citizen of the United States of America, and a resident of the city of Chicago, county 5 of Cook, and State of Illinois, have invented certain new and useful Improvements in Processes for Vaporizing Liquids, of which the following is a specification.

My invention relates to a process for vaporizing kerosene, crude oil and other liquids which are not volatile at ordinary temperatures, and has for its object the production of a superior process by which such volatilization is brought about.

15 It is well known that if a gas be compressed it will increase in temperature. Thus, if air at 32 degrees, Fahr., be compressed to one-half of its volume, its temperature will be raised to 193 degrees. If 20 the compressed air be then permitted to expand, under ordinary conditions, to its original pressure, the temperature will fall to 32 degrees. It is also known, however, that if a compressed gas be permitted to expand 25 under what is known as "free expansion", the expansion will occur without a corresponding fall in temperature. The condition for free expansion is that in which the expanding gas performs no work.

30 In the process to be hereinafter described I take advantage of this fact to produce an expansion which approximates free expansion by causing such expansion to occur under conditions in which it will perform 35 less mechanical work than that consumed in compressing the gas. The term "free expansion" as hereinafter used will mean, not the free expansion known in science, but that approximation to it which I use in carrying 40 out my process.

Heat and work are convertible into each other, and the mechanical equivalent of heat is represented as approximately 779 foot-pounds equal 1 B. T. U. If I should take 45 air at atmospheric pressure into a compressor and, in compressing it, use 1,558 foot-pounds of work, and then expand it to its original pressure under conditions in which it would perform only 779 foot- 50 pounds of work, there would remain in it one unit of heat, and this extra unit of heat would cause the air to be at a higher temperature than when entering the compressor.

It is also known that each liquid has a 55 boiling point of its own at atmospheric pres-

sure, and that the boiling point increases with the pressure. Thus, the boiling point of water at atmospheric pressure is 212 degrees, while at one hundred pounds to the square inch above atmosphere, the boiling 60 point is at 338 degrees. If water at 337 degrees and under one hundred pounds pressure should have that pressure reduced to atmospheric pressure, the water would boil. In carrying out my process I use this principle in conjunction with the principle of free expansion previously mentioned.

65 The accompanying drawing, partly in section and partly in elevation, shows an apparatus which may be used in carrying out 70 my process. In said drawing, 1 is a cylinder in which is a piston 2 reciprocated by a crank 3 and connecting rod 4. The crank is driven by power applied in any convenient manner to the shaft 5.

75 In the cylinder wall are small holes 6 through which air and finely divided oil enter when the piston is at the upper end of its stroke. In the bottom of the cylinder is a port closed by a valve 7 supported by a 80 stiff spring 8. A nut 9 serves as a means for adjusting the tension of the spring.

When the piston is in the position shown 85 in the drawing, air and oil enter the holes 6 to fill the cylinder. The proportions may be anything desired to meet particular circumstances. For the practically complete vaporization of kerosene the proportions may be about five or six parts by weight of air to one part of oil. As the piston descends it first closes the ports 6 and then compresses the air within the cylinder. When the pressure is sufficient to overcome the spring 8, the valve 7 opens suddenly 90 and permits the air and oil to escape into the 95 chamber 10, from which it is conveyed by the pipe 11. If the pipe 11 is connected to the manifold of an engine there is a suction on the pipe which leaves the pressure in the chamber 10 slightly below that of the atmosphere. Under these conditions the air in expanding will perform much less work than that consumed in compressing it with the result that the air is hot when flowing into 100 pipe 11.

105 The temperature in the cylinder will depend directly upon the pressure. There is a temperature which, if reached, will cause an explosion to occur in the cylinder. The tension of the spring 8 is adjusted so that the 110

valve 7 will open just before this temperature is reached, and this tension is determined independently by experiment for each kind of oil and for the particular conditions under which it is intended to operate. When a large amount of oil is injected into the cylinder for each stroke of the piston, the pressure may be higher than when only a small amount is injected. The reason for 10 this is that the oil absorbs a considerable amount of the heat of compression during the time compression takes place, and the more oil there is present the more the actual temperature will be reduced.

15 The oil which enters the cylinder is finely divided, either by passing through the small holes 6 or by means of some special spraying device, and as the temperature of the air increases by the descent of the piston the 20 little globules of oil in the air are heated to a high temperature. The smaller the globules the more perfectly they will be heated in the brief period of compression and the more perfectly the process will operate.

25 By this means the actual temperature of the oil in the globules is raised above the boiling point of the oil used, but actual vaporization is very slow or entirely held in abeyance by the great pressure in the surrounding air. The instant the valve 7 is opened, 30 however, the pressure is reduced, and the oil vaporizes under the reduced pressure by reason of its internal heat.

From the foregoing it will be apparent 35 that the critical things involved are the temperature obtained during compression, and the boiling point of the oil after expansion takes place. The more widely these two 40 temperatures are separated the more rapidly the oil may be vaporized, and the process is designed to separate them as widely as possible. The process is carried out, first, by a free expansion of air previously heated by

compression, and second, by the internal heat of the oil acquired during compression 45 and operating after expansion to vaporize the oil under the reduced pressure. Air at high temperature and low pressure obtained by compression and subsequent free expansion facilitates the vaporization of the oil 50 by the internal heat gained during compression.

What I claim is:

1. The process of vaporizing an oil which consists in mixing air and finely divided oil, 55 in compressing the mixture to obtain a high temperature in both air and oil, and in expanding and thereby vaporizing the oil under conditions which will reduce pressure without correspondingly reducing temperature. 60

2. The process of vaporizing an oil which consists in mixing the liquid and air, in compressing the air to obtain a high temperature therein, and in suddenly expanding and 65 thereby vaporizing the oil.

3. The process of vaporizing a liquid which consists in heating the liquid by contact with air at a high pressure and temperature, and then reducing the pressure of the 70 air so that the liquid may be vaporized by its internal heat under the reduced pressure.

4. The process of vaporizing oil which consists in subjecting a mixture of oil and air to a pressure which will raise the temperature of the mixture to a point near to but slightly below the flash point of said mixture, and then in expanding the air to a pressure substantially equal to atmospheric pressure, the air and oil being in contact 75 with each other during such expansion.

5. The process of vaporizing oil which consists in subjecting it to contact with air under compression and subsequent free expansion and thereby vaporizing the oil.

NILS EMEL NORSTROM.
